US0D1084000S

(12) **United States Design Patent** (10) Patent No.: **US D1,084,000 S**
 Kato et al. (45) Date of Patent: ** Jul. 15, 2025

(54) **DISPLAY SCREEN OR PORTION THEREOF WITH GRAPHICAL USER INTERFACE**

(71) Applicant: **TOYOTA JIDOSHA KABUSHIKI KAISHA**, Toyota (JP)

(72) Inventors: **Yasutomo Kato**, Okazaki (JP); **Hinata Ichikawa**, Nisshin (JP)

(73) Assignee: **TOYOTA JIDOSHA KABUSHIKI KAISHA**, Toyota (JP)

(**) Term: **15 Years**

(21) Appl. No.: **29/937,390**

(22) Filed: **Apr. 15, 2024**

(30) **Foreign Application Priority Data**

(57) **CLAIM**

The ornamental design for a display screen or portion thereof with graphical user interface as shown and described.

DESCRIPTION

The sole FIGURE shows a front view of a display screen or portion thereof with graphical user interface showing our new design.

The peripheral dashed broken lines depict a display screen or portion thereof, and form no part of the claimed design. The broken lines within the peripheral dashed broken lines depict portions of the graphical user interface which form no part of the claimed design.
